(57) **CLAIM**

The ornamental design for a screen unit for projector, as shown and described.

DESCRIPTION

FIG. 1 is a front-perspective view of a screen unit for projector in an open position;

FIG. 2 is a rear-perspective view thereof;

FIG. 3 is a front-perspective view thereof showing an unclaimed projector attached thereto;

FIG. 4 is a front elevational view of the screen unit for projector in an open position;

FIG. 5 is a rear elevational view thereof;

FIG. 6 is a left side elevational view thereof;

FIG. 7 is a right side elevational view thereof;

FIG. 8 is a top plan view thereof;

FIG. 9 is bottom plan view thereof; and,

FIG. 10 is a front-perspective view of the screen unit for projector in a closed position.

The broken lines depict environmental subject matter only and form no part of the claimed design.
